TAPE OF A VENETIAN BLIND OR SIMILAR
ARTICLE

Antonio S. Emmite, Dickinson, Tex.

Application April 3, 1953, Serial No. 24,349

Term of patent 14 years

(Cl. D21—6)

To all whom it may concern:

Be it known that I, Antonio S. Emmite, a citizen of the United States and residing at Dickinson, county of Galveston, State of Texas, have invented a new, original, and ornamental Design for a Clip for Attaching a Slat to a Cross Tape of a Venetian Blind or Similar Article, of which the following is a specification, reference being made to the accompanying drawing, forming a part thereof.

Figure 1 is a top perspective view of a clip for attaching a slat to a cross tape of a Venetian blind or similar article, showing my new design;

Figure 2 is a bottom perspective view thereof; and

Figure 3 is a side elevational view thereof.

I claim:

The ornamental design for a clip for attaching a slat to a cross tape of a Venetian blind or similar article, as shown.
